UNITED STATES PATENT OFFICE.

GEORGE H. GILMAN, OF ST. PAUL, MINNESOTA.

APPARATUS FOR MANIPULATING BRAKES ON RAILWAY-CARS.

1,159,581.

Specification of Letters Patent.

Patented Nov. 9, 1915.

Application filed October 16, 1914. Serial No. 866,999.

To all whom it may concern:

Be it known that I, GEORGE H. GILMAN, a citizen of the United States, residing at St. Paul, in the county of Ramsey and 5 State of Minnesota, have invented certain new and useful Improvements in Apparatus for Manipulating Brakes on Railway-Cars, of which the following is a specification.

My invention relates to apparatus for 10 manipulating brakes on railway cars, and has for its principal object to provide a simple, inexpensive and compact form of apparatus for setting and releasing the brakes of a railway car.

15 The mechanism most frequently employed for operating by hand the brakes of a railway car comprises a brake staff provided at the upper end with a hand wheel, or other means for revolving the same, the chain 20 attached to the pull rod operating the brake beams being wound on the other end of the staff, or on a drum thereon. The brake staff is held in the position setting the brakes ordinarily by means of a ratchet and dog.

25 My invention provides in mechanism of this type means for revolving the brake staff and for holding it in the set position of the brakes which allows the brakes to be gradually released instead of suddenly and 30 violently, and by means of which the power is applied gradually and evenly to the brake staff in setting the brakes; whereby the labor of the trainmen is lessened and the danger due to the possibility of breakage 35 of the apparatus is minimized.

The invention provides further, in the preferred embodiment of the invention, a mechanism for revolving the brake staff to apply the brakes to the wheels which does 40 not require any specific device for holding the brakes in their set position, the apparatus remaining in any position to which it may be set until positively moved therefrom by a reverse movement of the hand 45 operated member.

The invention has for further objects such other new and improved constructions, arrangements and devices relating to mechanism for operating the brakes of railway 50 cars as will be hereinafter described and claimed.

The invention is illustrated, in certain preferred embodiments, in the accompanying drawings wherein—

55 Figure 1 is a fragmentary end elevation of a gondola car shown as fitted with the

brake controlling apparatus of my invention. Fig. 2 is a vertical sectional view through the apparatus in a plane parallel to the end of the car. Fig. 3 is a sectional plan on line 3—3 of Fig. 2. Fig. 4 is a view, in perspective, of the casting, fixed to the end of the car, on which the movable parts of the apparatus are mounted. Fig. 5 is a fragmentary view, in perspective, of the 60 brake staff. Fig. 6 is a similar view of the reciprocating element for revolving the 65 brake staff. Fig. 7 is a fragmentary end elevation of a railway car showing, partly in section, a modified construction. Fig. 8 70 is a sectional plan taken on line 8—8 of Fig. 7, and Fig. 9 is a sectional view on line 9—9 of Fig. 8.

Like characters of reference designate like parts in the several figures of the 75 drawings.

The brake manipulating apparatus of my invention is shown as applied to a gondola car, the body of which is designated 10. The apparatus might readily be applied, 80 with certain obvious modifications, to freight cars of other types and also to passenger cars.

11 is a brake staff revolvably mounted in 85 bearings provided by the usual platform 12 and bracket 13. The chain 14, attached to the pull rod 15, which operates upon the brake beams through the usual levers (not shown), may be attached directly to and wound upon the end of the brake staff 11 90 or, as shown in the drawings, the brake staff may be provided at its lower end with a drum 16 on which the chain is wound.

17 is a tubular actuating member surrounding the upper end of the brake staff 95 and formed internally with the double threading 18 engaged by the spiral projections or threads 19 on the upper end of the staff. The member 17 is formed with a slide 20 which fits into a guideway 21 100 formed on a casting 22 which is secured to the end of the car. The casting 22 is provided with brackets 23, 24, formed with bearings between which is arranged a worm gear 25 having a shaft 26 provided at its upper end with a hand wheel 27 or other suitable means for revolving it. The worm wheel 25 engages with a worm rack 28 on the actuating member 17.

A guard 22^a is preferably provided for 110 the worm gear 25 and that part of the rack 28 with which the gear is meshed.

The brakes are set by manipulation of the hand wheel 27. The engagement of the worm gear 25 with the rack 28 raises the actuating member 17. The threaded engagement between the actuating member 17 and the brake staff causes the latter to revolve when the former is moved lengthwise thereof. In this form of apparatus no special device is necessary for holding the brakes in the set position. To release the brakes it is simply necessary to turn the hand wheel in the direction reverse to that setting the brakes. The power is applied to the brake staff gradually and the movement of the parts of the apparatus during the release of the brakes is gradual instead of being sudden and violent as is the case when the ordinary brake staff is released by kicking the dog out of its ratchet. The forces exerted in setting the brakes are so distributed that there is little danger of any part of the apparatus breaking. This eliminates a frequent cause of accidents to trainmen in the switching of cars. The fact that the brakes are released by a gradual turning of the hand wheel, instead of by the sudden and violent movement which takes place when the dog is kicked out of engagement with the ratchet wheel of the ordinary brake staff, eliminates another cause of injury to trainmen in the manipulation of the brakes.

It will be seen that a car having the usual hand operated brake staff can be equipped with the improvement above described by changes and substitution of parts which may be easily made at a small cost. For the original brake staff is substituted one provided at its upper end with threads or projections adapted to be engaged by the threading of the actuating member 17. The pull rod and chain of the original installation are retained. In this connection it is noted that while the chain is claimed as such in the claims appended hereto I intend to include by the term any suitable flexible member capable of being wound upon the brake staff or its drum.

In Figs. 7 to 9 inclusive, I have shown a modified construction in which a lever instead of a worm shaft is employed for raising the actuating element by means of which the brake staff is revolved. The brake staff 11 may be the same in construction as that previously described. The actuating element 29 is formed with a slide 30 which fits into a guideway 31 formed on a casting 32 secured to the end of the car 33. The actuating element 29, instead of being formed with a worm rack, is provided with teeth 34, the under surfaces of which are horizontal and the upper surfaces formed with a down slant. 35 is an operating lever pivoted at its inner end to a casting 36 hinged to a curved bracket 37 on the casting 32 by means of a pintle 38. The lever 35 terminates in

a pointed nose 39 adapted to engage with the teeth 34. The lever is formed with an angular slot 40 through which extends a bolt 41 rigid with the casting 36. The lever is rocked on the bolt 41 as a fulcrum and by engaging with the teeth 34 raises the actuating element 29. The slotted connection between the lever and the casting 36 permits the lever to be withdrawn from engagement with the teeth in raising the lever from the horizontal position. 75

Arranged in a housing 42 in the lower part of the casting 36 is a detent 43 adapted to engage the teeth 34 and provided with a stem 44 which extends through the back of the housing. A spiral spring 45 surrounds the stem 44. When the lever 35 and casting 36 are in the position indicated by the full lines in Fig. 8 the actuating element 29 may be raised by operation of the lever, thereby revolving the brake staff 11 so as to set the brakes. To release the brakes the lever 35 and casting 36 are given a pivotal movement horizontally, on pintle 38 as an axis, to the position indicated by the dotted lines 90 in Fig. 8. This movement withdraws the detent from the teeth 34, permitting a relative movement between the actuating element and the brake staff which allows the brake shoes to be moved away from the 95 wheels. 85

While I have described my invention as embodied in certain preferred constructions, it will be obvious that modification might be devised without departure from the principles of the invention. Therefore I do not wish to be understood as limiting the invention to the exact constructions, arrangements and devices shown except so far as so limited by the express language of the 105 claims. 100

I claim:

1. The combination with a car provided with brakes and apparatus for setting the same comprising a chain, of a brake staff on one end of which said chain is adapted to be wound, means for revolubly supporting the brake staff on the car and holding the same against longitudinal movement, an actuating element movable longitudinally of the 115 brake staff, having a threaded engagement therewith and formed with a series of teeth arranged longitudinally thereof, a shaft parallel to the brake staff revolubly mounted on the car, held against endwise movement and provided with a hand operated member, and a worm on said shaft engaged with the teeth on said actuating element. 120

2. The combination with a car provided with brakes and apparatus for setting the same comprising a chain, of a brake staff on one end of which said chain is adapted to be wound, means for revolubly supporting the brake staff on the car and holding the same against longitudinal movement, an ac- 130

tuating element movable longitudinally of the brake staff, having a threaded engagement therewith and formed with a series of teeth arranged longitudinally thereof, a 5 shaft parallel to the brake staff revolvably mounted on the car, held against endwise movement and provided with a hand operated member, and means operated by revolving said shaft for imparting longitudinal 10 movement to said actuating member.

3. The combination with a car provided with brakes and apparatus for setting the same comprising a chain, of a brake staff on one end of which said chain is adapted to be 15 wound, means for revolvably supporting the brake staff on the car and holding the same against longitudinal movement, an actuating element movable longitudinally of the brake staff, having a threaded engagement there- 20 with and formed with a series of teeth arranged longitudinally thereof, and means engaging said teeth for imparting longitudinal movement to said actuating element.

4. The combination with a car provided 25 with brakes and apparatus for setting the same comprising a chain, of a brake staff on one end of which said chain is adapted to be wound, means for revolvably supporting the brake staff on the car and holding the same 30 against longitudinal movement, an actuating element movable longitudinally of the brake staff and having a threaded engagement therewith, and means for imparting longitudinal 35 movement to said actuating element.

5. The combination with a car provided 35 with brakes and apparatus for setting the

same comprising a chain, of a brake staff on one end of which said chain is adapted to be wound, means for revolvably supporting the brake staff on the car and holding the same 40 against longitudinal movement, an actuating element extending over the end of the brake staff, having a threaded engagement therewith and provided with a slide and a series of longitudinally arranged teeth, a 45 guide way on the car to receive said slide, a shaft parallel to the brake staff, revolvably mounted on the car, held against endwise movement and provided with a hand operating member, and a worm on said shaft en- 50 gaged with the teeth on said actuating element.

6. In apparatus for operating the brakes on a railway car, the combination with a casting formed with a channeled guideway 55 and with a pair of brackets spaced apart, of a worm gear revolvably mounted between said brackets having a shaft provided with a hand wheel, an actuating element formed with a slide fitted into said guideway and 60 with a worm rack engaged by said worm gear, said actuating element having a threaded bore, and a brake staff, the upper end of which extends into the threaded bore 65 of said actuating element and is provided with threads engaging with the threading of said actuating element.
